UNITED STATES PATENT OFFICE

2,560,267

HAIRBAND

Barbara R. Baker and Florence C. Zartman,
New York, N. Y.

Application May 31, 1950, Serial No. 165,332

4 Claims. (Cl. 132—46)

1

This device relates to a head band adapted to be worn for the purpose of covering, after the manner of a cap or visor, a woman's hair while recently prepared curls are setting, and while the curling pins are still in use.

One of the advantageous features of this head band is due to its inherent tendency to remain in position. This is due in part to a clamping strip or flexible resilient element built into the band and which is concealed from view. Thus the band tends to embrace the brow of the wearer and yieldingly and gently grips the sides of the head of the wearer.

The above and additional essential features which characterize the device of this improved band lend themselves to incorporation in bands having ornamental and striking configurations which enhance rather than detract from the appearance of the wearer.

The above and additional features and advantages of the head band of this invention are more fully described and claimed in the following specification and claims and will be understood from the text and the accompanying drawing, in which:

Fig. 1 is a side view of the band illustrating the device as worn;

Fig. 2 is a top plan view of the band of this invention when not worn, and illustrating the normal configuration of the forward portion of the band when not in use;

Fig. 3 is a sectional view such as taken on the line 3—3 of Fig. 1, illustrating the length of the resilient clamping strip as located in the forward and brow portion of the band and intermediate the cloth plies of the band; and

Fig. 4 is a face view of the strip of which the band is made showing its general configuration before the darts are added to give it curvature to fit the head of a wearer.

Referring in detail to the several figures of the drawings, it will be observed by reference to Fig. 4 that the article is prepared from elongated strips of flexible fabric, one lengthwise edge of which may be substantially straight, the opposite edge being curved or scalloped depending on the artistic effect to be provided for sales appeal. Necessarily the band has at least two layers, plies, of cloth. Preferably the outer or display layer is of some attractive cloth in suitable colors. The opposite face of the band is desirably formed of terry cloth, toweling, thus to serve a useful function when the band is applied to the wearer's head while the hair and curls are damp.

In the several views of the drawings, the outer

2

layer is indicated at 1 and the inner layer is indicated at 2. From a manufacturing standpoint, it is conceivable that the inner and outer plies may be formed from a single piece folded at a middle point, the line of fold constituting one end of the ultimate band. By reference to Figs. 2 and 3, it will be observed that the outer ply 1 is continued from end to end and occupies the outer display position completely there-around, even after the snap fasteners are secured. Similarly, it will be observed from Figs. 2 and 3 that the inner covering 2 constitutes the sole head and hair engaging surface.

Fastening means for securing the opposite ends 15 of the band together are indicated by the use of conventional snap elements having sockets 3 and studs 4.

The several plies of fabric are secured together around the marginal edges by stitching indicated 20 at 5. The securing of the several plies together may be accomplished by any other suitable method if preferable to stitching. However, it is desirable that the marginal edges of the band be so secured together that the plies are folded inwardly so that the raw edges of the cloth or other fabric is thus concealed. In Fig. 2, which is a plan view, it will be observed that the inner and outer plies with the turned in edges are illustrated.

One of the important features of this band relates to the incorporation of a clamping band 6 which extends around the brow portion of the band from approximately ear to ear. This band is an elongated strip, preferably of a plastic material. It should be rust proof and resistant to water. It should be relatively narrow, as shown in Figs. 1 and 4 at 6^a. Preferably also the clamping strip 6 should be located adjacent the upper marginal edge so that the clamping action is insured while the forward portion of the band can be of absorbent and decorative cloth and also have artistic configuration which otherwise might be interrupted if the clamping band were located at a forward position. As shown in Fig. 1, the presence of the band provides a slight bulge or raised area, as indicated at 6^a. Endwise movement of the clamping band 6 is limited by suitable stitching or fastening means. A convenient arrangement for performing this function is provided in the present band by incorporating darts, as shown at 7 at opposite sides of the band and approximately in the region of the ears of the wearer. The darts are formed by drawing together portions of the straight upper edge of the band with the result that the curvature of

the band to fit the head is effected and the straight band, shown in Fig. 4, is thus brought into a configuration represented by that shown in Fig. 1. In Fig. 4, at 8, there is indicated, in dotted lines, the approximate location of the lines of fold which may be followed when forming the darts.

In Fig. 2, the band is shown in plan view and with the end portions of the plastic strips extending toward each other, almost suggestive of an incomplete circle. In Fig. 2, the rear portion of the band extends upwardly in the figure and it will be understood that this portion is of soft material and does not contain any stiffening element.

In Fig. 3, there is illustrated a sectional view taken on the line 3-3 of Fig. 1. This view shows the curvature of the plastic strip and brow portion of the band when the band is in use, and thus with the ends of the plastic strip spread apart while yieldingly gripping the side of the wearer's head.

From the foregoing, it will be clear that the present invention is not limited to the use of any particular type of cloth or to the material of the band 6 provided the latter is flexible, resilient and waterproof and has the characteristics outlined in the foregoing. It will also be clear that the configuration of the lower edge of the band may be varied for ornamental purposes. The band illustrated in Figures 1 and 4 provides a lower marginal edge suggestive of a short visor. However, that configuration may be modified and the outer surface of the band may be decorated as desired.

We claim:

1. In a hair band, an elongated strip of flexible fabric of double ply of sufficient length to encircle the brow and lower rear portion of the scalp, means to secure together the opposite ends of said strip to form a band adapted to encircle the head, and an elongated flexible resilient clamping element positioned between said plies and extending lengthwise of said strip across the brow portion and having its ends located about midway of the length of the band when the ends of the strip are connected.

2. In a hair band, an elongated strip of flexible fabric of double ply of sufficient length to encircle the brow and lower rear portion of the scalp, means to secure together the opposite ends of said strip to form a band adapted to encircle the head, and an elongated flexible resilient clamping element positioned between said plies and extending lengthwise of said strip across the brow portion and having its ends located about midway of the length of the band when the ends of the strip are connected, said clamping

element being provided with a curve intermediate its length and its ends being yieldable and resiliently pointed toward one another, whereby the band tends to grip the head of the wearer.

3. In a hair band, an elongated strip of flexible fabric of multiple ply of sufficient length to extend across the brow and to the region of the ears and having sufficient width to extend upwardly from the forward portion of the scalp so as to cover a substantial area of the hair at the front and sides of the head of the wearer, and said band including a portion adapted to extend around the rear of the wearer's head at the lower portion of the scalp, and an elongated flexible resilient clamping element located between adjacent plies of said brow covering portion and extending lengthwise thereof and having its ends located adjacent the ends of the brow covering portion of said strip, the ends of said clamping element being yieldably and resiliently projecting toward each other whereby the clamping element and its enclosing strip tend to grip the head of the wearer.

4. In a hair band, an elongated strip of flexible fabric of multiple ply of sufficient length to extend across the brow and to the region of the ears and having sufficient width to extend upwardly from the forward portion of the scalp so as to cover a substantial area of the hair at the front and sides of the head of the wearer, and said band including a portion adapted to extend around the rear of the wearer's head at the lower portion of the scalp, and an elongated flexible resilient clamping element located between adjacent plies of said brow covering portion adjacent the upper margin thereof and extending lengthwise thereof and having its ends located adjacent the ends of the brow covering portion of said strip, the ends of said clamping element being yieldably and resiliently projecting toward each other whereby the clamping element and its enclosing strip tend to grip the head of the wearer.
